UNITED STATES PATENT OFFICE.

PIETER CORNELIS TROUWBORST AND PETRUS JOHANNES THOMODOUS ARTS, OF ROTTERDAM, AND WILLEM HENDRIK ANTON ELINK SCHUURMAN, OF THE HAGUE, NETHERLANDS.

SHIP'S HATCH.

Application filed August 17, 1927, Serial No. 213,684, and in the Netherlands May 12, 1925.

Our present invention relates to ships' hatches and its object is a construction enabling the hatchway to be opened and closed in a simple and reliable manner with a minimum loss of time and to prevent accidents during their operation. With this object in view, we suggest to employ rolling shutters movable athwart-ships and each extending through half the width of the hatchway, the shutters on one side of the hatchway being adapted to be operated simultaneously or separately, as the case may be, by one single member, such as a handle.

In order that our said invention may be well understood, we shall now proceed to describe the same with reference to the annexed diagrammatic drawing, on which:

Fig. 1 is a plan view of a hatchway with hatches in accordance with our invention and,

Fig. 2 is a cross sectional elevation taken along the line II—II in Fig. 1.

The coamings of the hatchway are designated by 5, the headledges by 6, the shifting beams by 7. These shifting beams are provided with rollers 8, by means of which they can travel over the coamings 5, in the longitudinal direction of the hatchway, and further with the usual means (not shown) whereby they can be locked in position. Each shifting beam is provided on either

side with a groove 9 serving to guide a hatch in the form of a rolling shutter 10. Each shutter consists of a comparatively great number of planks 11 disposed side by side in the longitudinal direction of the hatchway and hinged to one another by means of joints secured thereto on the bottom side so as to be protected against direct contact with sea water. The port-side and the starboard-side hatches, when shut, meet in a vertical plane passing through the longitudinal axis of the hatchway.

The starboard-side hatches of the hatchway are rolled upon individual shafts or spindles 12 rotatably mounted within a casing formed by the starboard-side coaming 5, the deck plating 13, an upstanding plate 14 and a cover 15.

Keyed to each shaft 12 is a gear wheel 16. Other individual shafts 17, rotatably mounted within the above casing in parallel relation with the shafts 12, serve to open the hatches. To this end each shaft 17 carries

two pinions 18 in mesh with racks formed on the bottom side of the corresponding hatch, formed in any well known manner either by attaching segments of racks to the hatch or by forming the racks by indentations in the hatch, and also a gear 18^a. A shaft 19, running through the full length of the said casing and provided with a crank 20 on either end, is provided, parallel with each shaft 12 and 17, with a sleeve 21 adapted for lengthwise movement over shaft 19 secured to rotate therewith. Said sleeve carries two gears 22, 23 adapted to mesh with gears 16 and 18^a, respectively, and so spaced that, when gears 16 and 22 are in mesh, gears 23 and 18^a are out of mesh, and vice versa. By means of a handle 24, sleeve 21 can be moved lengthwise over shaft 19 either to operatively couple this shaft with shaft 12 or shaft 17, or to disengage it from both shafts 12, 17. Rotation of the shaft 12 by reason of the flexible hatch being secured thereto in any well known manner through the gears 22 and 16 moves the hatch to open position and the engagement of the gear 18 with the rack formed on the hatch when said gear is driven by the gear 23 moves the hatch to closed position.

The operating mechanism of the port-side hatches is identical with the one just described.

The mode of operation of our new apparatus so far described will now be understood by anyone skilled in the art. By means of the shaft 19, which may, if necessary, be coupled with a prime mover such as a steam winch, all starboard-side (or port-side) hatches can be opened or shut simultaneously, provided that the sleeves 21 on said shaft have all been set in the proper position. It is, however, as well possible to open or to shut only one or more distinct hatches, as circumstances require.

As will be seen, each shifting beam is provided in its central portion with two pairs of vertical holes 25 adapted to receive bolts 100 which also pass through corresponding holes in the hatches, whereby the latter may be locked in their closed positions.

The drawing still shows an eye 26 secured to the free end of each hatch and so disposed that the eyes of two mating hatches, when shut, are in alignment and located in the vertical plane passing through the longi-

tudinal axis of the hatchway. It will be understood that, when all hatches are shut, a cable 27 can be passed through all eyes 26 and through corresponding eyes secured to the headledges 6, 7 and that it is only necessary to seal this cable in order to seal all the hatches.

What we claim is:—

In hatchways for ships, a plurality of 10 pairs of athwartships, oppositely disposed flexible slatted shutters, said pairs being arranged side by side in a fore and aft direction so as to cover a plurality of sections of the hatchway, common driving spindles for 15 all starboard and all port hatches, respectively, said spindle being adapted to be se-

lectively coupled with any one of said hatches, means for sealing all hatches of one hatchway by means of a common cable running in a fore and aft direction, eyes formed 20 on the inner ends of the hatch shutters and through which said cable passes, athwartships means serving as guides for the shutters and adapted, when said shutters are wound up to travel in a fore and aft direction along the coamings so as to clear the hatchway. 25

In testimony whereof we affix our signatures.

PIETER CORNELIS TROUWEORST.

PETRUS JOHANNES THEODORUS ARTS.

WILLEM HENDRIK ANTON ELINK SCHUURMAN.
